(57) **CLAIM**

The ornamental design for an inflatable water craft, as shown and described.

DESCRIPTION

FIG. 1 is a front angled view of the inflatable water craft.

FIG. 2 is a back angled view of the inflatable water craft.

FIG. 3 is a bottom angled view of the inflatable water craft.

FIG. 4 is a front view of the inflatable water craft.

FIG. 5 is a back view of the inflatable water craft.

FIG. 6 is a right side view of the inflatable water craft.

FIG. 7 is a left side view of the inflatable water craft.

FIG. 8 is a top view of the inflatable water craft; and,

FIG. 9 is a bottom view of the inflatable water craft.

The tow line illustrated in broken lines is environmental structure and does not form a portion of the claimed design.
